UNITED STATES PATENT OFFICE.

WILLIAM S. CRAIG, OF CHICAGO, ILLINOIS, ASSIGNOR TO FREDERICK G. LIBKE AND DIETRICH H. BRUNJES, OF SAME PLACE.

MACHINE FOR LABELING CANS.

SPECIFICATION forming part of Letters Patent No. 605,858, dated June 21, 1898.

Application filed May 7, 1895. Serial No. 548,409. (No model.)

To all whom it may concern:

Be it known that I, WILLIAM S. CRAIG, a citizen of the United States, residing at Chicago, in the county of Cook and State of Illinois, have invented a certain new and useful Improvement in Machines for Labeling Cans, which is fully set forth in the following specification, reference being had to the accompanying drawings, in which—

10 Figure 1 is a side elevation of my machine. Fig. 2 is a vertical longitudinal section of the left-hand portion of Fig. 1. Fig. 3 is a plan of the tracks and revolving mechanism shown in section in Fig. 2. Fig. 4 is a plan of the 15 paste-box at the upper end of the machine. Fig. 5 is a vertical longitudinal section of the said paste-box. Fig. 6 is an enlarged detail elevation of the locking and releasing mechanism at the upper end of the machine. Figs. 20 7, 8, and 9 are detail views, the last in plan, of parts of the said mechanism. Fig. 10 is a longitudinal vertical section of the label-holder and adjacent devices. Fig. 11 is a vertical cross-section of said label-holder. Fig. 25 12 is a vertical section of the paste-rollers shown at the left-hand side of Fig. 10. Fig. 13 is a plan of the power-supplying device and rolls near the center of the machine.

The object of my invention is to make a 30 machine in which the cans are automatically labeled as they pass through the same.

My invention consists in the mechanisms and combination of mechanisms hereinafter fully described and made the subject-matter 35 of the claims hereof.

In the accompanying drawings, A represents the main frame of my machine, which is composed of two side pieces A' A², supported at a suitable incline upon the legs C' C³ and 40 C² C⁴, respectively, of which legs only C' and C³ are shown. The side pieces A' and A² are held at the desired distance apart by cross-rods c, upon which they are adjustable laterally by means of screw-threads and nuts or 45 other suitable devices to give them the desired distance apart to receive the cans which are being labeled. On the inside of these side pieces I place tracks B' and B², upon which the 50 ends of the cans rest as they roll down the incline in the operation of labeling them.

Near the upper end of my machine I place a paste-box D, adjustably supported upon uprights D' D², the said paste-box being provided with a valve mechanism consisting of the tube D³, plug D⁴, and downwardly-projecting part D⁵ to operate the said plug upon the passage of the can and permit the outflow of paste through the port in the bottom of the paste-box. Under this paste-box and extending some distance downward between the side 60 pieces A' A² of the machine I place a flexible pad D⁶, so arranged between the tracks that the can as it rolls along the track will come in contact with the pad. The paste-box D is adjusted to such height that when the can 65 is placed on the tracks at the upper end of the machine in rolling downward it will hit against the part D⁵ and raise it sufficiently to allow the paste to pass out of the valve and flow upon the central portion of the outside 70 of the can, and as the can passes the valve it will spread the paste upon the pad, and the entire surface of the can between the tracks upon which the ends of the can rest becomes covered with the paste. When the 75 can has passed down over the pad, it drops from the track upon one end of the labels in a box full of labels, as is clearly shown in the case of the can X³ in Fig. 10 of the drawings. The can is held in this position by a locking 80 device consisting of two arms E' E², pivoted upon opposite sides of the frame upon the pivot E³, of a cross-rod E⁴, mounted in slots e' e² at the upper ends of said arms E' E², respectively, the said cross-rod E⁴ being retained in a yielding position within said slots by the springs e³ e⁴, adjustably mounted in the said slot, and of arms E⁵ E⁷, pivoted to the upper ends of E' E², respectively, their remaining ends being connected by a second 85 cross-rod E⁶, parallel to but in a different plane from E⁴. The arm E⁷ is connected with the side piece A² of the machine by a connecting-rod E⁸, pivoted at one end to the said arm E⁷ and at its other end to the said side 90 piece at E⁹. To the lower end of the arm E' is pivoted one end of the rod F at F'. The other end of the said rod F is pivoted to the crank-arm F², keyed upon the rock-shaft F³, which extends across between the tracks of 95 100

the machine at a point near the lower end thereof, as shown in Figs. 1 and 2, the said rock-shaft carrying a trip F^4 , which projects upward in the pathway of the cans. Upon 5 a can passing down the track at this point it will depress the trip F^4 and so through the rod F throw the locking device hereinafter described into the position shown in dotted lines in Fig. 6. By this movement the can 10 X^3 is allowed to pass downward, while the cross-rod E^6 , pressing against the can X^2 , prevents that can and those behind it from following the can X^3 . The spring F^5 now acts upon the crank-arm F^2 to restore it and 15 through it the locking device to normal position, as shown in full lines. Thereupon the cans X^2 , &c., roll down into the position previously occupied by X^3 , &c., where they are checked and retained by the somewhat yielding 20 resistance of the cross-rod E^6 until the next unlocking operation of the locking device.

The label-holder consists of a bottom plate G , held in position by side pieces $g^3 g^4$. To 25 this bottom plate is pivoted a follower consisting of a top piece G' , two set-screws $g^3 g^4$ giving the bottom of the label-holder G the proper inclination, and of a post G^2 , mounted in a guide-tube G^3 , depending from the supports $g^5 g^6$, the upper end of the said post being rigid with G' , the lower end being provided 30 with a ratchet g^7 , upon which operates the pawl g^8 . An upward tendency is given to the post G^2 by a chain or cord g^9 , attached to 35 the lower end of said post, passing over a pulley g^{10} and the cam or pulley G^4 , to which is attached a weighted lever G^5 , the said cam and weighted lever being pivotally mounted in the depending supports G^6 . The label- 40 holder is prevented from rising beyond its proper position with reference to the tracks by the stop-roll H^3 , bearing against the lower end of the top label of the labels G^6 in the said label-holder. A secondary paste-box H 45 is suitably supported adjacent to the lower end of the label-holder, the said paste-box carrying a paste-roll H' and a distributing-roll H^2 , contacting with the stop-roll H^3 .

An adjustable plate H^4 is mounted upon 50 the downward projection H^6 of the paste-box, the upper edge of the said plate H^4 being caused to press against the roll H^3 by means of the spring H^5 . To one end of the stop-roll H^3 is secured a ratchet-wheel H^9 . A rod I , 55 adjustably pivoted at one end at I^3 to the arm E' of the locking mechanism, is forked at its lower end, the two branches I' and I^2 of the said fork carrying each a tooth engaging with the ratchet-wheel H^9 . As the arm E' periodically vibrates in the releasing of successive cans, a reciprocating motion is given to the rod I , which is transformed by the fork and ratchet-wheel device shown into a rotary motion from left to right on a part of the 60 stop-roll H^3 , whereby paste is spread upon the lower end of each label where that label

is to overlap its other end when rolled upon the can. The plate H^4 prevents the label from being drawn in between the rolls by the movement of the roller H^3 . 70

Upon the sides $A' A^2$ of the frame at a point toward the lower end of the label-holder are mounted two uprights K and K' , carrying a shaft K^{12} , upon which shaft are mounted upon opposite ends thereof the pulleys K^5 75 and K^7 , and between the said pulleys the roller K^2 . Motion is imparted to the said shaft by a belt K^6 upon the pulley K^5 . The roller K^2 carries an endless belt K^3 , which passes over the roller K^4 , mounted in the slots 80 K^{13} of the uprights $L L'$ farther down the machine. The pulley K^7 carries a belt K^8 , whereby its motion is imparted to the pulley M , later to be described. Pivoted to the uprights $K K'$ are the arms K^{10} , carrying at their 85 end the idle pulley or roller K^9 , which is adapted to press against the lower side of the belt K^3 to insure its contact with the upper surface of the cans as they roll down the machine. A spring K^{11} may connect the arm 90 K^{10} with the upright K to increase this effect of the idle-pulley K^9 . The motion of this belt is such as to carry the cans in the direction of their travel down the machine, and the effect of the belt is to press against the 95 label and lay it smoothly and evenly upon the can.

The uprights $L L'$, above referred to as carrying the roller K^4 in the slots K^{13} , are vertically adjustable upon the sides of the 100 frame in order to adapt the height of the belt K^3 to cans of different sizes. To the said uprights $L L'$ are pivoted two arms $N^2 N^3$, in which is mounted a shaft carrying upon its outer end the pulley N , driven by a belt M^2 , 105 which derives its motion from the pulley M' , which revolves with the pulley M , driven by the belt K^8 , hereinafter referred to. Between the arms $N^2 N^3$ is mounted the roller N' upon the shaft driven by the pulley N . Toward 110 the end of the said arms $N^2 N^3$ is attached a brush N^4 . A spring N^5 may be attached to the arm N^2 and the upright L to support the said arm and the mechanism it bears when there is no can present. 115

Upon the shaft M^3 are mounted the pulleys M and M' , above referred to, the former of which communicates motion to the shaft and so revolves the rollers M^4 and M^5 , also mounted upon the said shaft near the sides $A' A^2$ of 120 the frame and below the ends of the tracks B' and B^2 , respectively, their upper surfaces forming, so to speak, a continuation of the said tracks, which are here interrupted. The said tracks are continued again as the two 125 branches $b' b^2$ contract toward the center of the path of the cans. Farther down the machine they retake their previous position, attached to the sides of the framework thereof, as $B^3 B^4$.

To the branches $b' b^2$ are pivoted the arms $O' O^2$, carrying the stop-rollers $o' o^2$ at their 130

outer end and connected by a cross-rod O, which projects through the slots O³ in the sides of the frame. In the pathway of the cans, underneath the belt K³, is placed a trip P, carried by a rock-shaft P', which bears a crank-arm P² at its outer end. This trip is retained in its normal upright position by the spring P³, attached to the framework and to the crank-arm P². A rod P⁴ connects the crank-arm P² with the arm P⁵, pivoted at P⁶, the upper end of which arm P⁵ is adapted to support the rod O and so retain the stop-rolls o' o² in their raised position. A spring o³ connects the arm O² with the side of the frame A².

15 The operation of the mechanism last above described is as follows: When a can comes into the position X⁴, (shown in Figs. 1 and 2,) it is retained in that position by the stop-rolls o' o², which are prevented from yielding to the 20 downward tendency of the can by the pivoted arm P⁵, bearing against and supporting the cross-rod O. The can is revolved in this position by the rollers M⁴ M⁵, and the effect of the roller N' and the brush N⁴ is to press and 25 smooth the label firmly upon the can while it is being revolved. As another can advances down the track underneath the belt K³ it operates the trip P, by which the end of the arm P⁵ is withdrawn from its position under the 30 cross-rod O. The spring o³ yields as the stop-rolls o' o² are depressed by the weight of the can X⁴, whereby the said can is released and passes down the track and out of the machine. The spring o³ immediately raises again the 35 stop-rolls o' o² to permit the end of the arm P⁵ to retake its position as supporting the cross-rod O, which it does by virtue of the action of the spring P³. The stop-rolls are thus again in position to retain the next can.

40 From the above description it is apparent that my machine is simple in its construction and economical in its operation.

I claim—

1. In a machine for labeling cans, the main frame of the machine provided with inclined tracks down which the cans roll; a locking device for holding the unlabeled cans and releasing them one at a time to pass down the inclined tracks; comprising the yielding device, tent-rod E⁴, the rod E⁶ which is swung into detaining position at each operation, and supports for said rods; a tripping device operated by a can rolling down the tracks, said tripping device itself operating the above locking device, substantially as described.
2. In a machine for labeling cans, the main frame of the machine provided with inclined tracks down which the cans roll; a locking device for holding the unlabeled cans and releasing them one at a time to pass down the inclined tracks; comprising the yielding device, tent-rod E⁴, the rod E⁶ which is swung into detaining position at each operation, and supports for said rods; a tripping device comprising the trip F⁴, placed in the path of the rolling cans, the rock-shaft F³, crank-arm F² and a connection between the said crank-arm

and the said locking device, substantially as described.

3. In a machine for labeling cans, an escapement for single cans consisting of pivoted arms carrying a cross-bar for checking the cans, a frame pivoted to the arms, and having means for engaging a can, a link pivoted to said frame and to the machine-body, whereby movement of the arms in one direction will cause said frame to rise over the can, and movement thereof in the opposite direction will cause said frame to descend between the cans, and means for oscillating said escapement.

4. In a machine for labeling cans, a locking device for holding the unlabeled cans and releasing them one at a time, consisting of one or more pivoted arms E'; one or more arms E⁵ and E⁷ pivoted thereto; the brace E⁸, and the cross-rods E⁴ and E⁶, substantially as described.

5. In a machine for labeling cans, a locking device for holding the unlabeled cans and releasing them one at a time, consisting of one or more pivoted arms E'; one or more arms E⁵ and E⁷ pivoted thereto; the brace E⁸, and the cross-rods E⁴ and E⁶; in combination with a tripping device adapted to operate the said locking device, substantially as described.

6. In a machine for labeling cans, the rolls M⁴ and M⁵ placed in the path of the cans and rotated by appropriate mechanism; a roller N' yieldingly supported above and rotated in the same direction as the rolls M⁴ and M⁵; the said rolls bearing against the bottom and the said roller against the top of a can which has received its label for pressing down and smoothing the said label; a non-rotating brush bearing against the can and acting in conjunction with the roller N' for the same purpose; and movable stop-rolls for holding the can in position while it is rotated during the said smoothing, and for releasing it subsequently, substantially as described.

7. As an organized can-labeling apparatus, a framework carrying downwardly-inclined tracks, a paste-box for supplying paste to the surface of the can, a locking device for holding the cans in place and releasing one can while the rest are so held, a label-holder and labels, an endless belt mounted on revolving rollers above the tracks for pressing the label upon the can, a trip device in the track of the can for operating the locking mechanism above, a trip device for operating the stop-rolls hereinbelow mentioned, an upper roller for pressing the label upon the can as the said can is revolved, lower rolls for so revolving the said can, and stop-rolls for holding the can in position during such operation, substantially as described.

WILLIAM S. CRAIG.
